No. 858,131.

PATENTED JUNE 25, 1907.

H. J. AICHELE.
CAP FOR MAGAZINE TOOLS.
APPLICATION FILED JAN. 8, 1906.

UNITED STATES PATENT OFFICE.

HENRY J. AICHELE, OF PHILADELPHIA, PENNSYLVANIA, ASSIGNOR TO
NORTH BROTHERS MANUFACTURING COMPANY, OF PHILADELPHIA,
PENNSYLVANIA, A CORPORATION OF PENNSYLVANIA.

CAP FOR MAGAZINE-TOOLS.

No. 858,131.

Specification of Letters Patent.

Patented June 25, 1907.

Application filed January 8, 1906. Serial No. 295,118.

To all whom it may concern:

Be it known that I, HENRY J. AICHELE, a citizen of the United States, residing in Philadelphia, Pennsylvania, have invented 5 certain Improvements in Caps for Magazine-Tools, of which the following is a specification.

My invention relates to certain improvements in screw drivers or other handled tools, 10 in which a magazine is contained within the body of the handle.

The object of my invention is to provide a suitable cap for the magazine which will not interfere with the hand while the screw driver is in use and yet can be readily withdrawn when it is desired to gain access to the magazine. This object I attain in the following manner, reference being had to the accompanying drawing, in which:-

20 Figure 1, is a side view, partly in section, of a screw driver illustrating my invention; Fig. 2, is a view showing the handle reversed so as to allow the cap to be readily removed; Fig. 3, is a view similar to Fig. 1, with the cap 25 entirely removed; Fig. 4, is a detached view of the retaining ring; Figs. 5 and 6, are views of modifications of the invention, and Fig. 7, is a view of a modification in which a catch on the cap is arranged to enter a recess in 30 the walls of the magazine.

A is the handle of a screw driver, A' is the shank having, in the present instance, a detachable point b. It will be understood that the screw driver may be of the plain type as 35 shown, or of the ratchet type as desired, without departing from my invention.

In the type of screw driver illustrated the points b are made detachable and are of different widths and the separate points are contained in the magazine B, as shown in Fig. 1. This magazine is made by boring out the handle, as illustrated in Fig. 3, and in order to retain the points within the magazine I provide a cap D, this cap in the present 45 instance has a flange d which rests on the end of the handle and is preferably so shaped as to conform to the outline of the handle and the cap has a deep flange d' which also acts as a receptacle for the different points of the 50 screw driver when the cap is inverted, as shown in Fig. 2, or when it is detached.

In order to retain the cap in position I

form an annular groove a in the handle some distance from the end, as shown in the drawing, and insert in this groove a spring ring c, 55 Fig. 4, the ring projecting partly into the magazine B.

The cap D has an elongated annular recess d² in the walls of the flange d' so that when the cap D is forced into the magazine B it 60 will spread the ring c and can be pushed past the ring until the annular recess d² comes in line with the ring, when the ring will return to its normal position and rest in the recess, the ring allowing the cap to drop the full 65 depth into the magazine B when in the upright position, as shown in Fig. 1. The end of the flange d' is beveled and the edges of the recess are also beveled so that the cap can be forced past the split ring.

It would be impossible to readily remove the cap without an instrument and this defect would make the screw driver impracticable, but by making the annular groove elongated, as shown, so that when it is wished to 75 remove the cap all that is necessary is to invert the screw driver, as shown in Fig. 2, the cap will then drop out until the shoulder e comes in contact with the ring c, thus the cap is projected sufficiently to allow the hand to 80 grasp the cap and pull it out past the ring by force, the deep flange being sufficient to hold the several detachable points, the points extending beyond the cap sufficiently to allow them to be selected.

While I have illustrated my invention as applied to a detachable point screw driver it will be understood that it can be used in connection with a drill or other tool having detachable points or bits.

The flange may be a short flange extending only a short distance beyond the annular recess, as indicated in Fig. 5, or may extend the full depth of the magazine, or, in some instances, a fixed projection may be formed on 95 the body of the handle and the flange of the cap may have a series of longitudinal slots cut therein, as shown in Fig. 6, so that the flange will consist of a series of spring fingers. This modification may be made without departing from the essential feature of my invention.

While I have shown the cap with an annular flange d in addition to the deep flange d',

in some instances the flange d may be dispensed with.

In some instances I may provide a spring projection d' on the flange of the cap D' , as illustrated in Fig. 7, and form a groove in the handle, the groove being of such a width as to allow a certain amount of lost motion that the cap will be projected when the handle is inverted, then by pulling upon the cap the spring will be compressed so as to allow the cap to be bodily withdrawn from the handle.

I claim:—

1. The combination of a magazine, a removable flanged cap, the flange extending into the magazine, means for locking the cap to the body of the magazine, said lock having lost motion so that on the inversion of the magazine the cap will be projected a sufficient distance to be grasped by the hand, substantially as described.

2. The combination of a magazine, a projection extending into the magazine, a removable flanged cap, the flange fitting in the magazine and having a wide groove into which the projection extends so as to lock the cap in position but to allow it to have a certain limited movement when the magazine is inverted, substantially as described.

3. The combination of a magazine having an interior recess in its wall some distance from the one end thereof, a ring mounted in the recess and projecting into the magazine, a removable flanged cap for closing the magazine, said flange having a wide annular groove to allow for a certain amount of lost motion whereby when said magazine is inverted the cap will project beyond the end of

the magazine, substantially as and for the purpose described.

4. The combination of a magazine having an internal annular groove, a spring ring mounted in the groove and projecting into the hollow of the magazine, a removable cap having a flange adapted to enter the magazine, the said flange having a relatively wide annular groove into which the ring extends, said groove being so placed that when the magazine is upright the outer surface of the cap will be flush with the outside surface thereof, but will project when the magazine is inverted, substantially as described.

5. The combination of a magazine having an internal annular groove, a spring ring mounted in the groove, a removable cap having a relatively deep flange, a relatively wide annular recess in the flange of the cap having its edges beveled and the end of the flange being beveled so that the cap can be forced past the split ring and the ring will rest in the groove of the cap, there being sufficient lost motion to allow the cap to be flush with the outside surface of the ring when this is in an upright position and when said magazine is inverted to permit said cap to project beyond the end of the magazine so that it can be readily grasped, substantially as described.

In testimony whereof, I have signed my name to this specification, in the presence of two subscribing witnesses.

HENRY J. AICHELE.
